UNITED STATES PATENT OFFICE

JOHN M. BROWER, OF GRAND RAPIDS, MICHIGAN

DESIGN FOR A CHAIR

Application filed April 4, 1932. Serial No. 43,382. Term of patent 3½ years.

To all whom it may concern:

Be it known that I, JOHN M. BROWER, a citizen of the United States, residing at the city of Grand Rapids, in the county of Kent and State of Michigan, have invented a new, original, and ornamental Design for a Chair, of which the following is a specification, reference being had to the accompanying drawing, forming a part thereof.

Fig. 1 is a front perspective view of a chair showing my new design, and

Fig. 2 is a side perspective view of the same.

I claim:

The ornamental design for a chair, as shown.

JOHN M. BROWER.
